DESIGN FOR AN ARM WEAPON

Bernard J. Cosneck, St. Louis, Mo.

Application April 27, 1943, Serial No. 110,064

Term of patent 3½ years

To all whom it may concern:

Be it known that I, Bernard J. Cosneck, a citizen of the United States and a resident of the city of St. Louis, in the county of St. Louis City and State of Missouri, have invented a new, original, and ornamental Design for Arm Weapon, of which the following is a specification, reference being had to the accompanying drawing, forming a part thereof.

Fig. 1 is a perspective view of my arm weapon showing my design.

Fig. 2 is a top view thereof with part of the straps cut away.

Fig. 3 is a front elevational view thereof.

Fig. 4 is a side elevational view thereof with part of the straps cut away.

I claim:

The ornamental design for an arm weapon, substantially as shown.

BERNARD J. COSNECK.
